UNITED STATES PATENT OFFICE.

ALEXANDER WINTON, OF CLEVELAND, OHIO, ASSIGNOR TO WINTON GAS ENGINE AND MANUFACTURING COMPANY, OF CLEVELAND, OHIO.

GAS-ENGINE.

1,134,794.

Specification of Letters Patent.

Patented Apr. 6, 1915.

Application filed May 18, 1912. Serial No. 698,269.

To all whom it may concern:

Be it known that I, ALEXANDER WINTON, a citizen of the United States, residing at Cleveland, in the county of Cuyahoga and State of Ohio, have invented certain new and useful Improvements in Gas-Engines, of which the following is a specification, reference being had therein to the accompanying drawing.

10 My invention relates to improvements in gas engines.

The object of my invention is to provide an engine of this character in which the cylinders are cast in pairs with the intake and exhaust passages as a part of the castings, and when bolted together the said passages forming the exhaust and intake manifolds with the mixing device or carburetor connected at one end and the exhaust 20 at the opposite end, whereby a block or one unit engine is produced without the disadvantages heretofore found therein.

Another object of my invention is to provide an engine in which the intake and exhaust manifolds are side by side with the water-cooling system between the same whereby the charge is heated, yet there is no liability of the charge being ignited.

A still further object of my invention is to 30 provide a simple, cheap and effective engine having certain details of structure herein-after fully set forth.

In the accompanying drawings: Figure 1 is a side elevation partly in section of a gas 35 engine embodying my invention. Fig. 2 is a vertical sectional view taken on the line 1—1 of Fig. 1. Fig. 3 is a vertical sectional view showing how the exhaust enters the exhaust manifold.

40 Referring now to the drawings, 1, 2 and 3 represent the three castings, each having two cylinders and thus my improved engine is a six cylinder engine, while it is understood that any desired number of castings may be used to make a four or more cylinder engine. The said castings are connected together by blocks 4, which are provided with any desired packing for forming a tight joint with the cylinders, and 45 said blocks having openings 4¹ 4² to correspond with the openings in the cylinder castings as will be hereinafter more fully described.

The crank case is closed by the plates 5 55 and 6 and having openings closed by the

doors 7, whereby access may be readily had to the cranks of the engine.

The upper ends of the cylinder castings have cast integral therewith housings 6, which extend across the cylinder castings 60 and form the intake and the exhaust manifolds, which we will now proceed to describe.

The housings 6 formed integral with the cylinder castings are provided with central exhaust passages 7, horizontally arranged and having open ends which communicate with the openings 4² in the blocks 4. The said passages are surrounded by a space 8, which is in communication with the water-supply of the water circulating 70 cooling system of its respective cylinder. The housings above the water space 8 are provided with transverse passages 9, forming the intake for the gas of the engine, and which communicate with each other 75 through the openings 4¹ in the blocks 4.

The upper ends of the cylinders are open and have spaces 9' across the upper end which communicate with the intake passages 9. The ends of the castings are closed 80 by the heads 12, 13 and 14, which are of a hollow form and which are in communication with the water-cooling system of the engine. The said heads are provided at one side with passages 15, which are connected 85 together by the two pipes 16 and 17. The end head 14 has the water supply pipe 18 communicating with the passage 15 therein, while the opposite end of the passage 15 of the head 12 is closed by the plug 15'. Each 90 passage of the head has two openings 20 communicating with the water circulation of its respective cylinder in the head and said openings are controlled by the valves

21. By this arrangement it will be seen that 95 the desired amount of water is allowed to pass to each cylinder. The exhaust passage is also in communication with the space 9' by means of the passage 22, which extends through the intake passage 9. Surrounding the upper end of the passage 9 are 100 valve seats 23, upon which are seated the valves having operating rods extending into the crank case and operated by cams, as is well understood. The space 9', as heretofore stated, communicates with the ends of the cylinders and is therefore a passage for both the intake and the exhaust. The water circulation of each cylinder is in communication with the pipe 26, which extends along 105 110

the side of the cylinders adjacent their upper ends.

The water circulation of the cylinder being between the exhaust and the intake will 5 heat the intake and cause a better combustion of the fuel and at the same time prevent any liability of it becoming heated to such an extent that it will become ignited.

The end of the exhaust passage 7 is in 10 communication with the exhaust pipe 27, which is at one end of the engine, while the intake passage 9 has connected at the opposite end of the engine a pipe 9', which is in communication with the carbureter.

15 The housings 6 of each casting have their outer faces provided with openings covered by plates 28, whereby access may be readily had to the spaces 8 surrounding the exhaust manifolds 7, for the purpose of cleaning or 20 removing any deposit that may take place in the said spaces.

Having thus described my invention, what I claim and desire to secure by Letters Patent is:

25 1. A gas engine, comprising cast cylinders joined together with blocks, and said castings having housings forming the exhausts and inlets and connected by said blocks.

2. A gas engine, comprising cast cylinders 30 joined together with blocks and said casting having a housing forming exhausts and inlets with the water circulation of the cylinder separating the same, and said inlets and exhausts communicated by the blocks.

35 3. A gas engine, comprising cast cylinders joined together by blocks and said castings having housings formed integral therewith and between which the blocks extend, said housings having intake passages at their 40 upper end and exhaust passages in their lower end communicating with the exhaust passages of the other cylinder through the blocks and the exhaust passages communicating with the ends of the cylinders.

45 4. A gas engine comprising cast cylinders having exhaust and intake manifolds formed integral therewith, and blocks between the cylinders and having passages communicating the exhaust and intake mani- 50 folds of the castings.

5. A gas engine comprising cast cylinders having housings formed integral therewith, said housings having exhaust manifolds ad-

jacent their lower ends, and intake manifolds adjacent their upper end and separated 55 from the exhaust manifold by the water cooling system of the cylinders, said manifolds being connected with the upper ends of the cylinders through separate passages.

6. A gas engine comprising cylinders cast 60 in pairs and having housings formed integral therewith, said housings having exhaust manifolds adjacent their lower ends and surrounded by a space communicating with the water cooling system of the cylinders, said 65 housings having intake manifolds above the exhausts, passages communicating the exhausts and intakes with the end of their respective cylinders and valves controlling said passages.

7. A gas engine comprising cylinders cast in pairs, housings formed integral with the cylinders and having intake and exhaust manifolds extending horizontally therethrough, blocks between the cylinders and having openings connecting the intake and the exhaust manifolds of the castings, cylinder heads closing the ends of the casting and having water supply passages therein and valves controlling the supply of water from 80 said passages to the head, whereby the water cooling system of each cylinder is supplied with the desired amount of water.

8. A gas engine, comprising cylinders cast in pairs and having open ended housings cast 85 therewith and when bolted together form the intake and exhaust manifolds for the engine, an exhaust pipe connected to the exhaust manifold at one end of the engine and a gas supply connected to the intake manifold at the opposite end of the cylinder.

9. A gas engine comprising cylinders cast in pairs and having housings cast therewith with exhaust and intake passages and blocks between the cylinder castings and having 95 passages communicating with the passages in the cylinder castings and when bolted together forming exhaust and intake manifolds.

In testimony whereof I hereunto affix my 100 signature in the presence of two witnesses.

ALEXANDER WINTON.
